EXTERIOR LIGHTING FIXTURE

Donald E. Husby, Fairview Park, Ohio, assignor to
Westinghouse Electric Corporation

Filed Oct. 6, 1972, Ser. No. 295,619

Term of patent 14 years

Int. Cl. D26—03

U.S. Cl. D48—31

FIG. 1

FIG. 7

FIG. 2

FIG. 3

FIG. 4

FIG. 5

FIG. 6

FIG.8

FIG.9

FIG. 1 is an isometric view of an exterior lighting fixture illustrating my new design;

FIG. 2 is a top plan view thereof;

FIG. 3 is a front elevational view thereof;

FIG. 4 is a side elevational view thereof;

FIG. 5 is a rear elevational view thereof;

FIG. 6 is a bottom plan view thereof;

FIG. 7 is a side elevational view of a second embodiment of my new design;

FIG. 8 is a front elevational view thereof; and

FIG. 9 is a bottom plan view thereof.

I claim:

The ornamental design for an exterior lighting fixture, as shown and described.
